UNITED STATES PATENT OFFICE.

CHARLES F. MUELLER, OF ELIZABETH, NEW JERSEY.

DESIGN FOR A SQUARE-HEAD-NAIL SET.

45,049.

Specification for Design.

Patented Dec. 16, 1913.

Application filed September 11, 1913. Serial No. 789,397. Term of patent 7 years.

To all whom it may concern:

Be it known that I, CHARLES F. MUELLER, a citizen of the United States, residing at Elizabeth, in the county of Union and State of New Jersey, have invented a new, original, and ornamental Design for a Square-Head-Nail Set, of which the following is a specification, reference being had to the accompanying drawing, forming part thereof.

Figure 1 is a perspective view of my design. Fig. 2 is a top plan view of my design.

I claim:

The ornamental design for square head nail set, as shown.

CHARLES F. MUELLER.

Witnesses:

JOHN H. TRAUTMAN,
AUG. BUETHE.
